UNITED STATES PATENT OFFICE.

LINNAEUS E. BAKER, OF FORT WAYNE, INDIANA, ASSIGNOR TO WAYNE OIL TANK AND PUMP COMPANY, OF FORT WAYNE, INDIANA, A CORPORATION OF INDIANA.

SETTING-LATCH.

1,395,891.

Specification of Letters Patent.

Patented Nov. 1, 1921.

Application filed February 9, 1920. Serial No. 357,232.

To all whom it may concern:

Be it known that I, LINNAEUS E. BAKER, a citizen of the United States, residing at Fort Wayne, in the county of Allen and 5 State of Indiana, have invented new and useful Improvements in Setting-Latches, of which the following is a specification.

My improvement relates to self-measuring liquid dispensing apparatus of the type 10 having an elevated container from which the liquid dispensed flows by gravity; and particularly to means for setting the same to dispense a predetermined quantity of liquid, ordinarily called a setting latch.

15 My setting latch while normally holding the latch bar in contact with the notched scale by spring pressure, permits its ready release therefrom. It is simple in construction, and is readily adaptable to dispensing 20 apparatus so as to be easy to operate and conveniently located for use.

In the particular embodiment of my invention selected for illustration, my setting latch is applied to a dispensing apparatus 25 for outdoor use, having a vertically adjustable discharge pipe; in which—

Figure 1, is a front elevation of that portion of the apparatus which bears the notched scale, and shows the outer end of the 30 discharge pipe and the setting latch set in mid position, which is a discharging position,

Fig. 2, is a side elevation of the same with the setting latch set in filling position,

35 Fig. 3, shows the apparatus in the same position as Fig. 2, but in vertical section through the casing with the setting latch fully exposed to view, and

Fig. 4, is an enlarged view of the setting 40 latch only, shown in perspective, with parts broken away and in section to expose the spring and plunger.

Referring now to the drawings, e^2 , is the portion of the casing of the apparatus 45 shown; to which is fixed a flange, e^{13} , whose edges form a scale, e^{10} , provided with notches, e^{12} , graduated to gallons and half gallons. The notches and scale are on both flanges so as to be easily used and read from 50 either side of the apparatus.

A vertically adjustable discharge pipe, A, terminating above in an elevated container (not shown) has its bottom end formed of an L a^1 , with its horizontal portion extending 55 outwardly through the slot between the

flanges, e^{13} . The hose, I, is attached to the L.

The setting latch, D, is secured to the under side of the L, a^1 , by a pivot, d, in such manner as to oscillate at right angles to the plane passing through the axes of both 60 branches of the L, a^1 . A latch bar, d^1 , is fixed by the pin, d^2 , or in any other suitable manner in the latch block, d^3 , in such a position that the latch bar will enter any of the notches, e^{12} , when the latch, D, is in engaging 65 position.

Pointers, d^4 , fixed to the latch bar, d^1 , near the ends thereof indicate on the scales, e^{10} , the quantity of liquid required to be dispensed by the apparatus when the latch 70 has been set in accordance with the order.

A handle, d^5 , is secured to the latch block, d^3 , for convenience in manipulating the setting latch. The handle, d^5 , is drilled at, d^6 , to permit the shank of the plunger, d^7 , to 75 protrude through its upper side; and the latch block d^3 , is drilled to form a receptacle for the head of this plunger, and also to receive a spring, d^8 . This spring tends to keep the plunger in extreme protruded position 80 and when the hose I, is in position for use, its coupling, i^1 , keeps the plunger sufficiently depressed to cause it to hold the setting latch, D, securely against the notched scale whether in position for the latch bar, d^1 , to 85 enter one of the notches, e^{12} , or not.

A convenient way to lift the latch bar, d^1 , from any of the notches, e^{12} , of the scale, is to grasp the handle, d^5 , around the hose, I, and coupling, i^1 , compressing the spring, d^8 . 90 The discharge pipe, A, with its attendant parts including the hose and latch may then be easily adjusted upward or downward to any desired notch or indication on the scale, with the hand in same position as when disengaging the latch.

I claim as my invention and desire to secure by Letters Patent of the United States:—

1. A liquid vending apparatus comprising 100 a casing, an elevated container supported by the casing, an adjustable discharge pipe vertically movable within the container, a fixed scale carried by the casing, a setting latch carried by the discharge pipe and 105 means for normally holding the setting latch against the scale.

2. A liquid vending apparatus comprising 110 a casing, an elevated container supported by the casing, an adjustable discharge pipe

vertically movable within the casing and container, a fixed scale secured to the casing, a setting latch pivoted to the discharge pipe and having a bar adapted to engage notches on the scale, and means carried by the latch to normally hold the bar against the scale.

3. A liquid vending apparatus comprising a casing, an elevated container supported by the casing, an adjustable discharge pipe vertically movable within the casing and container, a scale secured to the casing, a setting latch pivoted to the discharge pipe and having a bar adapted to engage notches on the scale, a spring plunger carried by the latch and adapted to normally hold said bar against the scale and a handle on said latch for disengaging the bar from the scale.

4. A liquid vending apparatus comprising a casing, an elevated container supported by the casing, an adjustable discharge pipe vertically movable within the casing and container and extending through an elongated slot in the casing, scales secured to the casing at opposite sides of the elongated slot, a setting latch carried by the discharge pipe and having a horizontally extending bar adapted to enter corresponding notches in

the respective scales, and a spring plunger carried by the latch to normally hold the bar within the notches.

5. A liquid vending apparatus comprising a casing; an elevated container supported by the casing; a vertically adjustable discharge pipe movable within the container and having the outlet end extending through an elongated slot in the casing; notched scales fixed at opposite sides of said elongated slot; a setting latch pivotally mounted near the outlet end of the discharge pipe and having a horizontally extending bar adapted to enter corresponding notches in the respective scales; a spring pressed plunger carried by the latch and adapted to bear against the outer end of the discharge pipe to normally hold the bar within the notches; and a handle on said latch for disengaging the bar from the scales.

In testimony whereof I have hereunto set my hand in presence of two subscribing witnesses.
